UNITED STATES PATENT OFFICE.

CLAYTON M. JONES, OF JAMESTOWN, NEW YORK.

WRENCH.

Original application filed May 20, 1922, Serial No. 562,352. Divided and this application filed March 30, 1923. Serial No. 628,812.

To all whom it may concern:

Be it known that I, CLAYTON M. JONES, citizen of the United States, residing at Jamestown, in the county of Chautauqua and 5 State of New York, have invented certain new and useful Improvements in Wrenches, of which the following is a specification.

This invention relates to certain new and useful improvements in wrenches and is a division of my application for patent filed 10 May 20, 1922, Serial No. 562,352.

The primary object of the invention is to provide a wrench structure of greatly increased strength and at the same time one 15 of greatly cheapened cost, and further a structure of wrench which permits the use of a paneled handle extending into the sides of the fixed jaw or head, to thereby effect not only saving of material but to also 20 eliminate an area on the handle and head entailing difficulty and expense in polishing, the paneling at the same time providing a countersunk portion surrounding a portion of the knurl, so that the latter can be 25 easily rotated by the thumb and forefinger, but still is protected from accidental rotation, since the rotating surface of the knurl is positioned below the flat surface of the 30 wrench head. This structure also improves the appearance, and consequently enhances the salability of the wrench, and in addition lightens the weight thereof.

A further object of the invention is to provide a wrench structure which involves 35 a materially simplified and inexpensive form of screw for effecting adjustment of the movable jaw, which screws can be made in quantity production and which eliminate the necessity of positioning the knurl or the 40 screw by means of the very expensive tapping of corresponding threads in the knurl and the necessity of placing a slot in the end of screw as a means of screwing the knurl into position and also eliminating further 45 fastening of the knurl by means of a cotter- 50 pin, a tap screw or other method of preventing the knurl from rotating on the screw, all of which are very expensive operations. The result of the above construction is a 55 very simplified form of screw and shank and knurl, eliminating entirely all tapped threads and greatly reducing the cost.

A still further object of the invention is to afford a simplified and easily drilled bore 60 for the screw, which extends short of a side

of the head to thus not only save the cost of complete drilling of the bore, but to also leave a strong wall which protects the adjacent end of the screw; which prevents the bore from being jammed or upset thereby 60 preventing the rotating action of the screw, and which confines lubricant for the screw and protects the latter against the ingress of dirt and other foreign matter likely to impair easy and efficient operation of the 65 screw.

The invention has still further and other objects which will be later set forth and manifested in the course of the following 70 description.

In the drawings:—

Figure 1, is a side elevation of the invention;

Figure 2, is a fragmentary front edge elevation;

Figure 3, is a similar view of the rear edge;

Figure 4, is a fragmentary vertical sectional view;

Figure 5, is a view similar to Figure 4 of 80 a modified form of the invention, and

Figure 6, is a fragmentary front edge elevation of Figure 5.

In proceeding in accordance with the present invention, a handle 10 is provided 85 with a head 11 formed with a rigid jaw 12 having an angular brace 13, the latter being slotted at 14. The head 11 is formed with an upper barrel or bore 15 and a lower barrel or bore 17, the barrels being interconnected by a slot 20. The slot 14 extends through the rear end of the barrel 15 and substantially throughout the length of the latter. The barrels 15 and 17 are formed 90 by drilling operations, for which purpose the head 11 is originally made with projections 19 having flat end faces to afford drill seats, the projections being subsequently removed by cutting or grinding in finishing 95 of the tool.

The barrel 15 extends throughout the length of the wrench head and through the ends thereof, while the barrel 17 extends from the front side of the head to a point spaced from the rear side so as to leave a 105 solid wall 11^a which closes the rear end of the barrel 17. This wall 11^a greatly strengthens the structure and allows the panels 10^a on opposite sides of the handle to extend upwardly into the head 11. The 110

panels are formed by countersinking the handle and head sides. The inner end of the barrel 17 terminates at the inner side of an opening 18 which latter intersects the barrel 17 and has its outer wall defined by the inner face of the wall 11^a.

The adjustable jaw 16 has an angular web 21 formed with a cylindrical rack 21 having teeth 22, the rack being received in barrel 10 15 while the teeth 22 thereof extend into the barrel 17, the web being received in the slot 14.

A screw 23 is provided having a shank 25 to which latter a knurl 24 is affixed in any desired manner, the drawing by way of example illustrating the knurl as being cold shrunk onto the shank, as set forth in my said application. The slot 14 is formed by a saw-cut.

20 In the form of the invention depicted in Figures 5 and 6 of the drawings the front end of the upper barrel 15' is partially closed as indicated at 27, so as to further strengthen the wrench head, and protect the 25 end of the cylindrical rack 21 and upper barrel 15 from being upset by blows if the wrench is used as a hammer, which blows will impair or prevent free movement of the movable jaw, as well as keeping out 30 dirt and retaining lubricants. In this form of the invention the barrel 15' is drilled from the rear end of the wrench head and the slot 27 is formed by the saw which cuts the slot 14.

35 The screw is devoid of either a screw-driver receiving slot or kerf or any other means for securing same in position or for attaching the knurl thereto by extraneous fastenings consequently the screws and 40 knurls can be cheaply made in quantity production.

In assembly, the movable jaw is placed in 45 position, the knurl heated and positioned in its opening 18, whereupon, the screw is inserted in the lower barrel 17, and turned to engage with the rack teeth 22 until the shank 25 is completely inserted in the knurl opening, whereupon the knurl is chilled, causing same to be cold-shrunk onto 50 the screw stem.

It is particularly to be noted that the

lower barrel terminates short of the wall 11^a, and that the screw is afforded a bearing throughout the length of the lower barrel, also the knurled nut or knurl is carried by 55 the inner end of the screw which latter end is completely housed by the knurl, thus dispensing with the provision of a distinct bearing for each end of the screw, as generally practiced in the art. 60

What is claimed is:—

1. In a wrench, a handle having a head formed with a fixed jaw and upper and lower communicating barrels and also having a transverse opening intersecting the 65 lower barrel and spaced from the rear end of the head to provide an integral wall, a movable jaw having a rack fitted in the upper barrel and having its teeth extending into the lower barrel, a perforated knurled 70 nut in the opening, and a screw in the lower barrel having a shank rigidly secured in said perforation of the nut and spaced from said wall of the head, said wall extending completely over the outer end of 75 the screw shank so as to conceal same.

2. In a wrench, a handle having a head formed with a fixed jaw and upper and lower communicating barrels and also having a transverse opening intersecting the 80 lower barrel and spaced from the rear end of the head to provide an integral wall, a movable jaw having a rack fitted in the upper barrel and having its teeth extending into the lower barrel, a perforated knurled 85 nut in the opening, and a screw in the lower barrel having a shank rigidly secured in said perforation of the nut and spaced from said wall of the head, said wall extending completely over the outer end of the screw 90 shank so as to conceal same, the handle having depressed panel-forming parts in its opposite side faces extending at the upper ends thereof into the head, and at least to the axis of the knurl so as to afford access to 95 the latter in rotation thereof, the respective inner sides of the integral wall bounding the adjacent upper end portions of the corresponding panel-forming parts.

In testimony whereof I affix my signature. 100

CLAYTON M. JONES.
